INJECTOR

Irenee P. Pedrick, Philadelphia, Pa., assignor to
 William Sellers & Company, Incorporated,
 Philadelphia, Pa., a corporation of Pennsylvania

Application April 8, 1941, Serial No. 387,375

5 Claims. (Cl. 103—275)

This invention relates to an improvement in injectors, such as are used for the supply of water to steam boilers.

As is known, injectors have heretofore been provided with an overflow valve and a line check valve so arranged that the overflow valve will be controlled through the medium of the line check valve, to the end that the overflow valve will be closed when the line check valve opens and will be free to open when the line check valve is closed. Such a structure is, for example, disclosed in United States Patent No. 1,743,684, dated January 14, 1930, to Irene P. Pedrick.

Now in accordance with this invention there is provided in an injector an improved structure for the operation of the overflow valve under the control of the line check valve.

Having now indicated in a general way the nature and purpose of this invention, I will proceed to a detailed description of a preferred embodiment thereof with reference to the accompanying drawing, in which the single figure is a partial vertical sectional view of an injector embodying a preferred embodiment of this invention.

With reference to the drawing, 1 indicates a steam nozzle and 2 a water nozzle, both arranged to discharge into a set of combining tubes and forcing tubes 3, 3, which deliver into a delivery chamber 4. The tubes 3, 3 are provided with annular openings 5, 5 which communicate with an overflow chamber 6, the outlet 7 from which is controlled by an overflow valve 8. The delivery chamber 4 is provided with an outlet to a conduit 9, which leads to a boiler, the outlet being controlled by a line check valve 10.

A duct 11, connecting at its lower end with a conduit 12, extends into the delivery chamber 4 beneath the line check valve 10, and is closed at its upper end by a pilot valve 13 having a guide 14 extending into the duct. The valve 13 is provided with a stem 15, which extends into a chamber 16 formed on the check valve 10 and closed by a stop 17 through which stem 15 slidably passes. The end of the stem 15 within the chamber is provided with a head 18.

As will now be observed, when the line check valve 10 is closed the valve 13 will drop by gravity and will close the end of duct 11. On the other hand, when the line check valve 10 is fully opened, under delivery pressure in the delivery chamber 4, the valve 13 will be open by virtue of the engagement of head 18 with stop 17 in the opening movement of the check valve.

The conduit 12 opens into a chamber 19

formed above the overflow valve 8 and into which extends a Sylphon bellows 20 secured to a ring 21, slideable in a guide member 22 presenting a seat 26. A pin 23 having a head 24 secured to the Sylphon bellows 20 extends centrally through a bore in the ring 21 to a point slightly spaced from the upper end of an extension 25 of the overflow valve 8. The extension 25 extends through the ring 22 and into an enlargement of the bore in ring 21.

It will now be observed that if the line check valve 10 be opened under delivery pressure in chamber 4, the valve 13 will be opened and pressure from chamber 4 will pass through conduit 12 to chamber 19. Pressure in chamber 19 will be exerted on the Sylphon bellows, which will cause ring 21 to be forced onto the seat 26 and pin 23 to be engaged with the end of extension 25 to hold the overflow valve 8 closed.

If now the delivery pressure in chamber 4 falls, the line check valve 10 will close and in closing will permit valve 13 to close by gravity, thus closing duct 11. The pressure in chambers 19 and 4 will equalize through conduit 12, since excess pressure in chamber 19 will raise valve 13. Thus, any pressure which may be trapped in chamber 19 will be instantly dissipated. The overflow valve 8 will lift under delivery pressure and since it is of large area compared to the area of 24 and 21, there will be no delay until pressure in chamber 19 is dissipated or equalized with the pressure in chamber 4.

When the valve 8 lifts, the end of extension 25 will contact the shoulder 27, formed by the enlarged bore in ring 21, and ring 21, pin 23 and the Sylphon bellows 20 will be raised as a unit in the continued opening movement of valve 8.

When delivery pressure again obtains in chamber 4, pressure will obtain in chamber 19, through the opening of valve 13, and will cause the bellows 20, pin 23, ring 21 and valve 8 to move downwardly as a unit until ring 21 contacts the seat 26. Then the Sylphon bellows 20 will be compressed causing pin 23 to fully close valve 8 and maintain it closed until pressure in chamber 19 is again dissipated.

It will be understood that it is not intended that this invention be limited to the particular structure described above for illustrative purposes, since it will be obvious that various modification in detail may be made without departing from the scope of the claims appended hereto.

What I claim and desire to protect by Letters Patent is:

1. In an injector, a line check valve, an over-

flow valve, a Sylphon bellows, means for communicating pressure to said bellows when said line check valve is open and means affording an operative connection between said bellows and said overflow valve whereby said overflow valve will be closed under pressure operative on said bellows.

2. In an injector, a line check valve, an overflow valve, a Sylphon bellows, means for communicating pressure to said bellows when said line check valve is open and means affording an operative connection between said bellows and said overflow valve, said connection, overflow valve and the bellows being movable bodily as a unit throughout the major travel of said overflow valve and fixed means independent of said overflow valve to render said connection between said bellows and said overflow valve operative to effect a final closing movement of said overflow valve.

3. In an injector, a line check valve, an overflow valve, a Sylphon bellows, means including a pilot valve controlled by said line check valve for communicating pressure to said bellows when said line check valve is open and means secured to said bellows and spaced from said overflow valve when said overflow valve is in fully closed

position affording an operative connection between said bellows and said overflow valve whereby said overflow valve will be closed under pressure operative on said bellows.

5. 4. In an injector, a line check valve, an overflow valve, an extension on said overflow valve, a movable ring embracing said extension and presenting a shoulder to the end thereof, a guide for said ring providing a seat therefor, a Sylphon bellows secured to said ring, a pin secured interiorly to said bellows and extending through said ring to a point adjacent to the end of said extension and means including a pilot valve controlled by said line check valve for communicating pressure to said bellows exteriorly when said line check valve is open.

5. In an injector, a line check valve, an overflow valve, a Sylphon bellows, a movable support for said bellows, means forming an operative connection between said bellows and said overflow valve, means affording a stop for said support for said bellows operative in the closing movement of said overflow valve to render said connection operative to effect final closing movement of said overflow valve, and means including a pilot valve controlled by said line check valve for communicating pressure to said bellows exteriorly when said line check valve is open.

IRENEE P. PEDRICK.
